UNITED STATES PATENT OFFICE.

RUDOLPH M. HUNTER, OF PHILADELPHIA, PENNSYLVANIA.

FIRE-EXTINGUISHING SPRINKLER-NOZZLE.

1,032,548.

Specification of Letters Patent. Patented July 16, 1912.

Application filed April 27, 1911. Serial No. 623,607.

To all whom it may concern:

Be it known that I, RUDOLPH M. HUNTER, a citizen of the United States, and a resident of the city and county of Philadelphia, State of Pennsylvania, have invented an Improvement in Fire-Extinguishing Sprinkler-Nozzles, of which the following is a specification.

My invention has reference to fire extinguishing sprinkler nozzles and consists of certain improvements which are fully set forth in the following specification and shown in the accompanying drawings which form a part thereof.

15 The object of my invention is to provide a simple form of sprinkler nozzle adapted to normally close a discharge orifice for an extinguishing fluid but which will automatically open by a rise in temperature at 20 or adjacent to the nozzle for the purpose of liberating the water or other fluid and discharging it in the form of spray.

More particularly my object is to provide an inexpensive construction of sprinkler 25 nozzle which shall be easily made and adjusted and moreover which will disrupt itself with free discharge of the extinguishing fluid in case of a sufficient rise in temperature adjacent to the nozzle.

20 My invention consists of certain improvements which are fully disclosed in the accompanying drawings and described herein-after and more particularly defined in the claims.

35 Referring to the drawings, Figure 1 is a sectional elevation of an automatic sprinkler nozzle embodying my invention; Fig. 2 is a plan view of the same; and Fig. 3 is a perspective view of the strut, valve, and spraying devices.

A is an annular body provided with an inwardly directed annular flange C and a cylindrical flange B screw threaded upon its interior. Said body A is further provided with light upwardly extending housings H, terminating in a hub portion G. Screwing into the back or threaded flange portion B is a bushing D having a polygonal portion F by which it may be turned 40 and a screw threaded nipple E by which the fluid may be supplied. The bushing D has a chamber D' about which is an annular rim which operating with the annular part C of the body forms a clamp between which 45 the flexible diaphragms I and L are clamped.

These diaphragms are provided with central apertures I' and L' respectively, the aperture L' in the diaphragm L being slightly larger than the aperture I' of the diaphragm I. Furthermore the inner diaphragm L is preferably provided with openings M of suitable shape so that the fluid in the chamber D may act through the said openings of the diaphragm L upon the under surface of the outer diaphragm I and likewise may act upon the annular edge of the diaphragm I adjacent to the opening I' by reason of the fact of the projection of said edge inwardly with respect to the edge of the opening in the diaphragm L.

70 J is a valve piece preferably flat on the upper surface and spherical upon the under surface J² and in which further the flat upper surface is provided with a central recess J'. This valve being spherical will fit 75 into the aperture I' of the diaphragm I without requiring very accurate adjustment, and hence is easy of assemblage with the diaphragm I constituting a seat. To avoid all special machine work and to insure a 80 tight joint, I prefer to apply to the outer surface of the diaphragm adjacent to the aperture therein an annular line of soft metal K against which the spherical valve piece rests.

85 The valve piece J is pressed downward upon the diaphragm I by means of a suitable strut R and a tension screw O, the latter being screwed through the hub G of the housing and pressing upon the strut to force 90 it downward upon the valve piece. Referring more particularly to the strut structure R, it is composed of three parts, namely, a part R¹ pressing directly upon the valve piece, a part R² pressing directly against 95 the adjusting screw and abutment, and the adjusting screw and abutment, and the part R³ which locks the two parts R¹ and R² together and held in place by the fusible solder R⁴. The strut part R¹ is of a length substantially equal to the distance 100 between the valve piece J and the abutment Q of the screw O, is rounded on its lower part to form a pivot R⁵ which is centered in and capable of rotating in the recess J' on the top of the valve piece J, and its upper part is made straight to form an elongated bearing at right angles to the strut part. Furthermore, this part R¹ is provided with a rectangular opening R⁶. The strut portion R² is provided with a 105 110

flat face which rests against the flat face of the part R' and, at its upper end, it is provided with a reverse curve forming a socket groove R^6 into which the upper elongated edge of the part R' is received and upon which it bears, and an upwardly extending similar socket or groove R^5 parallel to the socket or groove R^6 but slightly to one side thereof. The lower part of the strut portion R^2 is provided with an aperture R^7 which comes into alignment with the aperture R^9 in the part R^1 and extending downward from the said aperture R^7 is a groove portion r . The third portion of the strut structure consists of the angular piece R^3 and comprises more specifically an extended flat portion which rests against the face of the strut part R^1 , a laterally extending portion r^2 which extends through the apertures R^1 and R^9 of the respective parts R' and R^2 , and the downwardly extending lug r^3 which is narrow and projects into the recess or groove r in the part R^2 . This part R^3 is securely soldered in position in connection with the parts R' and R^2 with fusible solder capable of melting at a comparatively low temperature, such as commonly employed in sprinkler nozzles. The narrow lug r^3 being led into the recess or groove r in the part R^2 acts to shield and protect this weak portion R^3 against injury or bending which might make it bind should the same be accidentally struck from any cause, as in shipping the sprinkler or through carelessness in handling or assemblage. Furthermore, because of the narrowness of this portion, it is desirable to give it proper support to prevent accidental lateral displacement sufficient to weaken the soldered connection and this is accomplished by setting this part r^3 into a groove portion r prior to the soldering of the parts in position.

The adjusting screw O is, as before stated, screwed through the hub G and has its lower end cut away on opposite sides to form upon the bottom of the screw a flat edge approximating a screw driver shape, the width, however, being only that of the normal diameter of the screw so that the screw may be removed from the housing when necessary and also for purposes of assembling the parts. This screw driver end of the screw or elongated bearing end Q of the adjusting screw O rests in the elongated socket or groove R^5 of the strut part R^2 , and hence tends, when adjusted, to cause the part R^2 to rotate about the elongated bearing R^6 upon the end of the strut part R' . As this rotation is prevented by the interlocking part R^3 soldered in position, it follows that the thrust of the screw O is transmitted almost directly upon the valve piece J . It is further evident that when rotating the screw O during the adjustment, the strut device is

rotated with it and the pivot R^8 of the strut device is free to rotate in the socket recess J' in the valve piece and without disturbing the valve piece itself. The outer end of the screw O is provided with the spraying disk P , which is provided with suitable notched flanges for breaking up and spraying the water or extinguishing fluid which is projected against it when the valve piece is liberated. This spraying disk P is formed integral with the adjusting screw O and acts as a means for rotating the same for purposes of adjustment.

I have shown in Fig. 3 the various elements making up the nozzle with the exception of the main frame and housing portions and the parts there shown are separated so as to give a general and clear idea of the shapes and forms of said parts in approximately the relative positions they assume, but spread slightly for purposes of elucidation.

In the operation of the nozzle the water or other fluid is held under pressure within the chamber D' , the same acting upon the flexible diaphragm I , L for pressing it against the valve piece J , the pressure upon the valve piece being adjusted by the screw O to depress the central portions of the diaphragms, as indicated in Fig. 1. If the surrounding temperature fuses the solder R^4 , the pressure of the water acting upon the under side of the diaphragms and valve piece will thrust the strut part R' upward and cause the lower portion of the part R^2 to be thrown out laterally, the same being permitted by the liberation of the locking part R^3 . When this rupture of the strut structure takes place, it itself parts and together with the valve piece is thrown upwardly by the pressure of the water or fluid beneath and this is assisted by the action of the water upon the diaphragms and by the elasticity of the diaphragms themselves, the object being to quickly separate and discharge the said strut structure and valve piece. In this manner, no chilling of the solder will be permitted before the strut structure parts are separated and when the several parts are forced away, there will be a clear passage for the extinguishing water in the direction of the distributor or spraying head or disk P by which the stream of water is broken up and spread in the form of spray. It will be observed that when the solder R^4 is first melted the spring action of the diaphragms I and L supplemented by the pressure of the water thereupon impart the first upward movement to the valve piece to thoroughly separate the parts R' , R^2 and R^3 before any passage is made between the valve piece and the diaphragm I for the passage of the water, and hence the device is proof against chilling of the solder from premature escape of the water.

In the manufacture of this improved nozzle, much economy exists from the simplicity both in the construction of the parts and in the manner of assemblage. It will readily be seen that the parts of the strut structure may be secured together as a separate part and then introduced between the valve piece and the screw O and then by the mere turning of the screw with the requisite pressure may be applied to the valve piece to firmly press it upon the diaphragm to insure a tight joint by simply rotating the screw together with the strut structure R. For these reasons, the strut structure is not only simple and effective in its construction and operation, but may be assembled at a minimum cost and without danger of defective adjustment.

While it is evident that the double diaphragms I, L are effective in increasing the elasticity and the tendency to liberate the valve piece when the strut structure is unsoldered, I do not restrict myself to the use of the second or perforated diaphragm L, as my improvements may be employed with the upper diaphragm I alone, if so desired, and while the exact construction shown in the drawings has proved most satisfactory in commercial adaptation of the invention, the minor details may be modified without departing from the spirit of the invention.

Having now described my invention what I claim as new and desire to secure by Letters Patent is:-

1. In a fire extinguishing sprinkler nozzle, the sprinkler head having a spring valve seat at all times normally subjected to the pressure within the head, combined with a valve piece, a clamping screw carried in the head and having an elongated transverse bearing, and a strut structure between the screw and valve piece consisting of two main flat members resting against each other and having apertures through them in alignment and the end of one of said members having an elongated transverse pivoted bearing near the end of the other member and having its other end engaging the valve piece to form a central rotatable pivot bearing, and the other member having an elongated transverse socket engaging the elongated transverse bearing of the clamping screw and further provided with a shielding recess r said members soldered together with fusible solder and the elongated transverse bearings being out of alignment, and a locking member having a narrow finger extending through the apertures in the other members and having its end received in the shielding recess r in one of said other members and said locking member soldered to

the respective other members aforesaid with fusible solder.

2. In a fire extinguishing sprinkler nozzle, the sprinkler head having a yoke or housing and a spring valve seat, combined with a valve piece therefor, a clamping screw in the housing having an elongated edge, and a multiple part strut having its parts secured together into a unit by fusible solder, said strut having a rotatable pivot connection with the center of the valve piece and a transverse hinge joint connection with the elongated edges of the clamping screw and also freely rotatable within the yoke or housing, whereby the rotation of the screw rotates the strut to adjust the tension of the valve upon its seat but does not rotate the valve piece.

3. In a fire extinguishing sprinkler nozzle, the combination of the housing portion having an annular seat, a body portion screwed unto the annular seat, a sheet metal diaphragm clamped in position in the annular seat and having a valve seat surrounded with a soft metal seal, a valve piece having a spherical seating surface and simultaneously resting upon the edge of the opening in the sheet metal diaphragm and on the soft metal seal, a second diaphragm of sheet metal also clamped in the annular seat and having a central aperture of greater diameter than the valve seat aperture, and means for forcing the valve piece upon the seat held in place by fusible solder.

4. In a fire extinguishing sprinkler nozzle, the combination of the housing portion having an annular seat, a body portion screwed into the annular seat, a sheet metal diaphragm clamped in position in the annular seat and having a valve seat surrounded with a soft metal seal, a valve piece having a spherical seating surface and simultaneously resting upon the edge of the opening in the sheet metal diaphragm and on the soft metal seal, a second diaphragm of sheet metal also clamped in the annular seat and having a central aperture of greater diameter than the valve seat aperture, and also having annularly arranged openings for permitting the pressure of the water to act upon the first mentioned sheet metal diaphragm at places between it and the last mentioned diaphragm, and means for forcing the valve piece upon the seat held in place by fusible solder.

In testimony of which invention, I hereunto set my hand.
